UNITED STATES PATENT OFFICE.

CARL WINKLER, OF BERNE, SWITZERLAND.

CYLINDER FLAT-FORM PRINTING-MACHINE.

1,295,661.

Specification of Letters Patent. Patented Feb. 25, 1919.

Application filed November 6, 1915. Serial No. 59,969.

To all whom it may concern:

Be it known that I, CARL WINKLER, a citizen of the Swiss Republic, residing at Berne, in the Swiss Republic, have invented new and useful Improvements in Cylinder Flat-Form Printing-Machines, of which the following is a specification.

My present invention relates to improvements in cylinder-flat-form printing machines, and the improvements consist in a new arrangement of the parts of the driving mechanism, in the use of devices to obtain greater safety and more convenient manipulation, and further in effecting an economy 15 of space, which is of great importance for printers.

In the following specification the invention is described with reference to the drawings, in which:

20 Fig. 1 is a side elevation of a cylinder-flat-form printing machine, which is provided with the improvements forming the subject-matter of the invention.

Fig. 2 shows a plan of the same after removing the impression cylinder together with the form and the upper table,

Fig. 3 shows a section through two parts of the driving mechanism connected together by means of a safety breaking piece.

30 Fig. 4 is a section through the coupling provided in the driving gear.

Fig. 5, a side elevation of the coupling itself.

Fig. 6 represents the special starting gear 35 in the non-operative position.

Fig. 7 shows the same device in the operative position,

Fig. 8, is a plan of the same.

Fig. 9 shows a front view and Fig. 10 a 40 section of a hand operated driving mechanism in the position of use.

a is the impression cylinder, which oscillates backward and forward. To this cylinder is fed the sheet to be printed from a feed table *b*, and the cylinder leads said sheet over the carriage *c*, which reciprocates backward and forward underneath the cylinder *a*. The carriage is driven by a motor *d* through the agency of the cones *e*, *f*, belt *g*, shaft *h*, 45 pulleys *i*, *k*, belt *l*, shaft *m*, toothed wheels *n*, *o*, connecting rod *p* and toothed wheel *q*, which engages in the two toothed racks *r*, *s*, of which the upper one is attached to the carriage *c*, so that said carriage is reciprocated in known manner. The paper carrying cylinder can be driven, for example, by

a spur-wheel *a'* attached thereto engaging in a toothed rack *c'* fastened to the carriage. The pulley *k* is constructed as a fly wheel. Further fly-wheels *k'*, *k''* can be provided at 60 any other convenient parts of the driving mechanism, for example on the shaft *h*, or on the motor shaft, as indicated in dotted lines in Fig. 2.

Of essential importance in this construction is the arrangement of the driving organs including the motor and the fly-wheels inside the machine. By this arrangement space is saved and much greater security is obtained in operation; further, disturbances, 70 which would be caused by foreign bodies falling into the gear, are avoided.

In order to obtain still greater safety a breaking piece is arranged between a driving and a driven part of the gear, which piece 75 breaks when the machine is subjected to too great a strain, and thus the machine is caused to stop. For this purpose an arm *t* is keyed to the driving shaft *m*. The spur-wheel *n* is not fastened on the driving shaft 80 *m* direct, but by means of a pin *t'* secured to the arm *t*. As soon as the stress on the machine exceeds a certain amount the pin *t* is clipped, and the machine comes to rest.

Further, in the driving mechanism a coupling is provided, which can be easily put in and out of action, for the purpose of stopping the machine without the usual brake device. This coupling, which is clearly shown in Figs. 4 and 5, consists of the friction disk *m'* keyed on the driving shaft *m*, and of a coupling disk *k* adapted to move longitudinally on the shaft *m* and partly on the hub of the friction disk *m'*, said disk *k* being driven by the belt *l*, and adapted to be 90 moved longitudinally through the instrumentality of the lever *m''*.

To operate the coupling it is preferable to use the link-gearing shown in Figs. 6, 7 and 8, which enables the machine to be put in and out of operation, and, if desired this can be done on both sides of the machine, without any fastening having to be used. This device depends for its action on the self-fastening property of a knee joint. 100 The arm *u* of a three-armed lever forms with the rod *u'* a knee joint *u''*. The other end of the rod *u'* is attached to the lever *u''*, which is fastened on the shaft *u'*. On this shaft is also fastened the lever *u''*, which 110 puts the coupling in and out of gear. The arm *u* moves the lever *u''* by means of the

rod u^7 , and the lever u^6 is keyed on the shaft u^8 .

By depressing the pedal u^9 the three-armed lever is turned until the arm u rests 5 on the stop u^{10} . This takes place when the knee joint u^2 is somewhat below a line connecting the centers u^{11} and u^{12} , and, in this position, the arm u , owing to the reaction of the coupling, is pressed against the stop u^{10} .

10 The coupling is accordingly put into action and the lever u^3 is held in position.

If, on arranging a lever u on each side of the machine, the two levers cannot be keyed on a common shaft (for example 15 owing to insufficient space) the coupling cannot be put out of operation on one side alone, because the knee joint on the opposite side would not be opened. By providing a second lever u^6 and rod u^7 it is rendered 20 possible to put the coupling in and out of operation on both sides of the machine, without any special fastening being necessary, because, on actuating one of the levers u , both knee joints u^2 are pushed through 25 the middle position by the rods u^7 and lever u^6 .

A further important feature of the invention is the arrangement of a mechanical device for adjusting the machine to various 30 printing speeds. As will be seen from Fig. 2 the device is combined with the machine in such a manner that the machine is not enlarged in any way. The belt g running over the cones e, f can be moved longitudinally of said cones by the screw spindle v and fork v' by means of a hand wheel v^2 , the speed of the machine being thus altered.

Because the lowest speed attainable with the cones is still too high to enable work to 40 be done on the cylinder, for example to wash or cover said cylinder and to effect adjustments of the mechanism, I provide a special device for obtaining a slow mechanical forward motion. The device consists of two friction disks w and w' which 45 are keyed on a spindle w^2 journaled in the lever w^3 . By moving the lever w^3 , which can be done by means of the lever arm w^4 , rod w^5 , bell crank lever w^6 and pedal w^7 , 50 the friction wheel w can be brought into contact with the hub w^8 of the driving wheel k . At the same time the disk w' presses against the friction disk w^9 , so that the quick rotation of the driving wheel k 55 is converted into a slow rotation of the disk w^9 on the shaft m , and the machine is accordingly driven very slowly.

Instead of the mechanical device hand 60 mechanism for slowly driving the machine forward, or even backward, can be used, In the construction shown in Figs. 9 and 10 the spur wheel x^2 fastened to the spindle x , which is adapted to turn and move longitudinally in the frame x' , engages in the 65 toothed crown x^3 screwed to the friction

disk m' . If therefore the spur-wheel x^2 is turned by means of the crank x^4 the clutch disk m' , and with it the entire machine is slowly turned. In order to put the spur-wheel x^2 out of engagement with the toothed crown x^3 when the gear proper is put into action, which is done by moving the fly wheel k longitudinally of shaft m , a roll x^6 is provided on a lever x^5 , which bears against said fly-wheel and is moved 70 when the clutch is put into operation by moving, the fly-wheel toward the friction disk m' . As a consequence the spindle x^7 and the lever x^8 secured to said spindle are turned somewhat, and the rod x^9 attached to the lever x^8 is pulled back against the tension of the spring x^{10} , so that the spur-wheel x^2 is released and is moved longitudinally by the spring x^{11} until it does not engage with the toothed crown x^3 . 80 The mechanical driving of the machine accordingly then takes place, without the hand gear being influenced. If after putting the mechanical driving out of action it is desired to put the hand gear into operation, it is only necessary to push in the shaft x against the tension of the spring x^{11} , and thus to bring the spur-wheel x^2 into engagement with the toothed crown x^3 , whereupon the spring x^{10} causes the pin x^9 90 to rise and keep the spur-wheel x^2 in its working position, so that the machine can be driven by hand again.

While the drawings show only one type of machine by way of example, yet it is 100 to be understood that I am not restricted to this type of machine.

What I claim and desire to secure by Letters Patent of the United States is:—

1. A printing machine comprising in combination, a reciprocating form, a coöperating impression cylinder, and actuating means for said form and cylinder including a shaft, a fly wheel loose upon said shaft and provided with a clutch element, means for imparting rotation to said fly wheel, a second clutch element adapted to rotate with said shaft and means to bring the clutch element of said fly wheel into engagement with said second clutch element, substantially as set forth. 105

2. A printing machine comprising in combination, a reciprocating form, a coöperating impression cylinder, and actuating means for said form and cylinder including a shaft, a fly wheel loose upon said shaft and provided with a clutch element, a second clutch element adapted to rotate with said shaft, means to bring the clutch element of said fly wheel into engagement with said second clutch element, a motor adapted to drive said fly wheel, and a second fly wheel on the shaft of said motor, substantially as set forth. 120

3. A printing machine comprising in com- 130

- bination, a reciprocating form, a coöperating impression cylinder, and actuating means for said form and cylinder including a shaft, a fly wheel loose upon said shaft and provided with a clutch element, a second clutch element adapted to rotate with said shaft, means to bring the clutch element of said fly wheel into engagement with said second clutch element, a second shaft in driving connection with said fly wheel, a fly wheel on said second shaft, a motor adapted to drive said second shaft, and a fly wheel on the shaft of said motor, substantially as set forth. 5 45
- 10 5. A printing machine comprising in combination a reciprocating form, a coöperating impression cylinder, and actuating means for said form and cylinder all in the outline of the machine frame, said means including a shaft, a fly wheel loose upon said shaft and provided with a clutch element, a second clutch element adapted to rotate with said shaft, means to bring the clutch element of said fly wheel into engagement with said second clutch element, a motor adapted to drive said fly wheel, and a hand operated device for driving said fly wheel, substantially as set forth. 60 50
- 15 6. A printing machine comprising in combination a reciprocating form, a coöperating impression cylinder, and actuating means for said form and cylinder including a shaft, a fly wheel loose upon said shaft and provided with a clutch element, a second clutch element adapted to rotate with said shaft, means to bring the clutch element of said fly wheel into engagement with said second clutch element, a motor adapted to drive said fly wheel, and a hand operated device for driving said fly wheel, substantially as set forth. 65 55
- 20 7. A printing machine comprising in combination a reciprocating form, a coöperating impression cylinder, and actuating means for said form and cylinder including a shaft, a fly wheel loose upon said shaft and provided with a clutch element, a second clutch element adapted to rotate with said shaft, means to bring the clutch element of said fly wheel into engagement with said second clutch element, a motor adapted to drive said fly wheel, and a hand operated device for driving said fly wheel, substantially as set forth. 70 60
- 25 8. A printing machine comprising in combination, a reciprocating form, a coöperating impression cylinder, and actuating means for said form and cylinder including a shaft, a fly wheel loose upon said shaft and provided with a clutch element, a second clutch element adapted to rotate with said shaft, means to bring the clutch element of said fly wheel into engagement with said second clutch element, a motor adapted to drive said fly wheel, a hand operated device for driving said fly wheel, and means for putting said hand operated driving device out of gear, when the motor is driving said fly wheel, substantially as set forth. 75 65
- 30 9. A printing machine comprising in combination, a reciprocating form, a coöperating impression cylinder, and actuating means for said form and cylinder including a shaft, a rotatable element loose upon the shaft and movable longitudinally thereon, a clutch element keyed to the shaft, means for imparting a different speed of rotation to the rotatable element, and a system of knee or double jointed levers for moving the rotatable element toward said clutch element and locking the same in the 80 70
- 35 adjusted position. 85
- 40 10. A printing machine comprising in combination, a reciprocating form, a coöperating impression cylinder, and actuating means for said form and cylinder including a shaft, a fly 80
